CLAIM

The ornamental design for a frame for a pressure washer, as shown and described.

DESCRIPTION

FIG. 1 is a front perspective of the frame;
FIG. 2 is a front elevation view thereof;
FIG. 3 is a rear elevation view thereof;
FIG. 4 is a right elevation view thereof;
FIG. 5 is a left elevation view thereof;
FIG. 6 is a top plan view thereof; and,
FIG. 7 is a bottom plan view thereof.

The broken lines showing portions of a frame are included for the purpose of illustrating environment and form no part of the claimed design.

1 Claim, 7 Drawing Sheets
